J. A. MITCHELL,
WATER LIFT.
APPLICATION FILED SEPT. 28, 1916.

Patented Oct. 30, 1917.

Inventor

J. A. MITCHELL

By Watson E. Coleman

Attorney

UNITED STATES PATENT OFFICE.

JAMES AMERICUS MITCHELL, OF McCROY, ARKANSAS.

WATER-LIFT.

1,244,631.

Specification of Letters Patent. Patented Oct. 30, 1917.

Application filed September 28, 1916. Serial No. 122,753.

To all whom it may concern:

Be it known that I, JAMES A. MITCHELL, a citizen of the United States, residing at McCroy, in the county of Woodruff and 5 State of Arkansas, have invented certain new and useful Improvements in Water-Lifts, of which the following is a specification, reference being had to the accompanying drawings.

10 This invention relates to certain improvements in water lifts and it is an object of the invention to provide a device of this general character whereby the water will be elevated under the influence of air pressure.

15 It is also an object of the invention to provide a novel and improved device of this general character wherein a controlling valve may be unseated under air pressure independently of the pressure employed in the elevation of the water, and whereby said pressure for unseating the valve serves to prevent accumulation of said or other foreign substance 25 upon the valve seat.

The invention consists in the details of construction and in the combination and arrangement of the several parts of my improved water lift whereby certain important 30 advantages are attained and the device is rendered simpler, less expensive and otherwise more convenient and advantageous for use, all as will be hereinafter more fully set forth.

35 The novel features of the invention will hereinafter be definitely claimed.

In order that my invention may be the better understood, I will now proceed to describe the same with reference to the accompanying 40 drawings, wherein is disclosed a view partly in section and partly in elevation of a water lift constructed in accordance with an embodiment of my invention.

As disclosed in the accompanying drawings, 45 1 denotes a tubular member of predetermined dimensions and adapted to be disposed within a source of water supply and for which reason the lower end portion thereof is pointed.

50 Adjacent its lower end the tubular member 1 is divided by the partition 2 while the portion of the walls of the member below said partition 2 is perforate, as at 3, in order to afford the requisite ingress of water without 55 in said member. The upper end portion of

the member 1 leads in any desired manner to a suitable source of discharge.

As herein embodied, the partition 2 is removable and is secured to the lower end portion of the pipe 4 leading from a suitable source of air under pressure and extending within the member 1, a portion of the member being provided with an opening 5 to permit the ready insertion or removal of the pipe 5 and the partition 2. The opening 5 is adapted to be closed by the cover 6.

As herein disclosed, the source of air supply comprises the tank T and in which air is adapted to be compressed in any preferred manner.

The lower end of the pipe 4 is provided with a restricted extension 7 which is returned relative to the pipe 4 and extends a predetermined distance above the partition 2, the upper end portion of said extension 7 having interposed therein a check valve 8 of any ordinary or preferred type. The extension 7 is adapted to terminate below the water level or line so that as the air is discharged through the extension 7, the water will be lifted or elevated as is believed to be self-evident.

The partition 2 to one side of the pipe 4 is provided with an opening 9 defined by a valve seat 10 and with which seat coacts 85 the ball valve 11 positioned within the upstanding cage 12 carried by the partition 2.

Leading from the tank T and extending within the tubular member 1 is a pipe 14 which extends below the partition 2 and terminates in an upturned portion 15 positioned substantially directly below the valve 11, and it will at once be self-evident that the air passing through said pipe 14 will serve to elevate the valve 11 and to prevent 95 the accumulation of sand or other foreign substance upon the seat 10.

Interposed in the pipe 14 and exterior of the member 1 is a valve 16 herein disclosed as of a globe type and whereby the 100 flow of the air under pressure through said pipe 14 is readily and conveniently controlled.

By having the pipes 4 and 14 engaged with the partition 2, it will be at once perceived that the same may be readily removed from within the member 1, although if preferred the device in its entirety can be readily and conveniently displaced.

From the foregoing description, it is 110

thought to be obvious that a water lift constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A water lift including a tubular member provided with an entrance opening, a partition insertible within said tubular member, a pipe secured to said partition and leading from a source of fluid under pressure, said pipe being provided with a returned extension.
2. A water lift including a tubular member provided with an entrance opening, a partition insertible within said tubular member, a pipe secured to said partition and leading from a source of fluid under pressure, said pipe being provided with a returned extension, said partition being provided with an opening, a valve coacting with

said opening, and means for unseating said valve.

3. A water lift including a tubular member provided with an entrance opening, a partition insertible within said tubular member, a pipe secured to said partition and leading from a source of fluid under pressure, said pipe being provided with a returned extension, said partition being provided with an opening, a valve coacting with said opening, and fluid means for unseating said valve.

4. A water lift including a tubular member provided with an entrance opening, a partition insertible within said tubular member, a pipe secured to said partition and leading from a source of fluid under pressure, said pipe being provided with a returned extension, said partition being provided with an opening, a valve coacting with said opening, and a pipe leading from a suitable source of fluid under pressure and extending through said partition and terminating in a returned portion discharging beneath the valve.

In testimony whereof, I hereunto affix my signature in the presence of two witnesses.

JAMES AMERICUS MITCHELL.

Witnesses:

W. B. KYLE,
Mrs. T. C. BULL.
